DICTATION MACHINE

Harry A. S. Howarth, Philadelphia, Pa., assignor
to Kingsbury Machine Works, Inc., Philadelphia, Pa., a corporation of Delaware

Application September 16, 1930, Serial No. 482,315

33 Claims. (Cl. 274—17)

This invention relates to phonographs, and more particularly to phonographs of the type employed as dictation machines.

One object of this invention is to provide a machine of the type characterized having its parts so arranged as to constitute a relatively flat unit that may be readily disposed in a drawer or other analogous compartment that is relatively shallow.

Another object of this invention is to provide a dictation machine which is so constructed that it may be readily disposed within a drawer and wherein the mouth piece and controlling elements are so disposed as to be conveniently accessible to the operator when the drawer is open by a relatively small amount.

Another object of this invention is to provide a dictation machine having parts movable into and out of a drawer or like compartment and provided with devices for assuring against injury to the parts by a closing of the drawer or other compartment at a time when any of the parts are projecting exteriorly thereof.

Another object of this invention is to provide a dictation machine adapted to be disposed within a drawer or similar compartment and having a mouth piece movable into and out of the drawer and which is so constructed that movement of the mouth piece into and out of the drawer automatically determines the operative relationship of some of the parts of the machine.

Another object of this invention is to provide a dictation machine adapted to be disposed within a desk or table drawer and which automatically moves its scale and indexing mechanism into operative relation with the top of the desk or table when the mouth piece is moved out of the drawer into operative position.

Another object of this invention is to provide a dictation machine adapted to be disposed within a drawer and having a mouth piece movable into and out of the drawer and which is so constructed that the drawer cannot be closed while the mouth piece is disposed exteriorly thereof.

Other objects of the invention will appear as the description thereof proceeds.

The invention is capable of receiving a variety of mechanical expressions, one of which is shown in the accompanying drawings, but it is to be expressly understood that the drawings are for purposes of illustration only and are not to be construed as a definition of the limits

of the invention, reference being had to the appended claims for that purpose.

Referring in detail to the drawings, wherein the same reference characters are employed to designate corresponding parts in the several figures:

Fig. 1 is a perspective view of a desk provided with a dictation machine embodying the present invention;

Fig. 2 is an enlarged end elevation of a machine embodying the present invention;

Fig. 3 is an enlarged plan view of said machine; and

Fig. 4 is a vertical section, on an enlarged scale and partly broken away, to exemplify one known mechanism suitable for simultaneously moving the feed screw and the recording and reproducing mechanism into their several operative and neutral positions with which the present invention may be associated.

In the form shown, the dictation machine generally designated A in Fig. 1 is disposed in a drawer B. While the machine has been illustrated as placed in the middle drawer of a conventional flat top desk, it will be readily appreciated that the machine can with equal facility be placed in a side drawer, as C in Fig. 1, or it can be placed in a drawer in any other suitable type of desk, or in a table, or in fact in any analogous compartment.

The dictation machine A, which may be of any suitable type and construction, is provided with a mouth piece D which is movable into and out of the drawer and which by its movement into and out of said drawer operatively disposes the scale and index mechanism E with respect to the top of the desk and may also automatically operate other control and safety devices as to be explained hereinafter.

As shown more in detail in Figs. 2 and 3, the dictation machine includes a base plate 10 on which is mounted a motor 11 of any suitable type or construction, but preferably an electric motor disposed within a suitable housing 12 carried by said base plate. Supported in any suitable way from said base plate is a mandrel 13 adapted to carry any usual or suitable tablet 14. Suitable mechanism is provided for driving the mandrel from the motor, as a belt 15 and pulleys 16 and 17, and said driving mechanism also preferably includes a suitable clutch 18 for starting and stopping the mandrel and feed mechanism. A suitable feed screw 19 driven by gearing 20 is provided for feeding the rectilinearly movable carriage 21 which is

adapted to slide on a guide rod 22 and carries a suitable feed nut 23 for cooperation with said feed screw. Any usual or suitable sound box 24, providing recording and reproducing mechanism, is mounted on said carriage and may be moved with respect to the carriage so as to bring either the recording or the reproducing mechanism into operative relationship with the tablet 14, said mechanism being also movable 5 into an intermediate or neutral position in which neither of said mechanisms is engaged with the tablet, as well understood in the art. The means for moving the recording and reproducing mechanism into neutral and operative 10 positions is controlled by a button 25 which is also operatively connected by the rod 26 to mechanism of any suitable character for moving the feed nut 23 into and out of engagement with the feed screw 19, said button being disposed at the front of the machine where it is readily accessible. As shown in Fig. 4, rod 26 is connected to an arm 91 projecting from the carriage and by which the position of the feed nut 23 is controlled. Also projecting from 15 the carriage is a second arm 92 connected by linkage 93 to a tubular member 94 which is mounted to reciprocate in the tubular portion 95 of the carriage with which the sound conduit communicates. Sound box 24 is pivotally 20 mounted in said tubular member 94 at 96, and the sound box neck carries a projection 97 which cooperates with a cam surface 98 on said tubular portion 95, so that the recording and reproducing styli are lifted from the record 25 tablet into a neutral position, simultaneously with the movement of the feed nut out of cooperative engagement with the feed screw, when the sound box is moved into an intermediate position, while the feed nut is engaged with the 30 feed screw when the sound box is moved forwardly or rearwardly into one of its operative 35 positions.

As so far described, the machine may be of any usual or suitable construction, the same 40 having been illustrated more or less diagrammatically because forming no part of the present invention in so far as the details of construction are concerned, and therefore the parts so far referred to are to be taken as typical of 45 the parts of any suitable phonograph or dictation machine.

In accordance with the present invention the parts, so far described are arranged in a compact unit having a relatively low height that 50 is adapted for installation in a desk drawer or analogous compartment. As shown, the mandrel 13 is disposed in horizontal alignment with the motor 11 and its housing 12, with the recording and reproducing mechanism and the associated feed mechanism as well as the parts next 55 to be described also substantially in horizontal alignment with said mandrel and therefore so arranged that the whole constitutes a relatively flat unit.

60 Leading from the recording and reproducing mechanism 24 is a suitable sound transmitting tube 30 which is attached to said mechanism and movable therewith, said tube being telescopically received within a tube 31 carried by brackets 65 32 from the base plate 10. Communicating with the tube 31 is an elbow 33 which may rotate with respect to the tube 31, or the tubes 31 and 33 may be connected to rotate together with respect to the brackets 32 and tube 30, so long as 70 the elbow 33 is capable of oscillating about a

horizontal axis determined by the axis of the tube 31. Swiveled on the end of the elbow 33 is a second elbow 34 which may move with respect to said elbow 33 about an axis in a plane disposed at right angles to the axis of movement of elbow 33. In order to give the elbow 34 suitable rigidity a bracket 35 is preferably secured to the elbow 33 and carries a pivot pin 36 which engages a lug 37 on the elbow 34, the axis of the pivot pin 36 coinciding with the axis of the communicating ends of the elbows 33 and 34. Hence the elbow 34 may be oscillated about an axis disposed at right angles to the axis of movement of the elbow 33, and therefore the outer end of said elbow 34 by reason of its capacity for movement about the two right angularly disposed axes is capable of universal motion. 80 85 90

Attached to the outer end of the elbow 34 is a tube 38 leading to a mouth piece 39, which may be of any suitable type and construction. 95 Tube 38 may be rigid, or as hereinafter pointed out more in detail, it may be flexible; if rigid, it may be made in one piece or it may be composed of telescopic sections as hereinafter referred to. It will therefore be perceived that by 100 reason of the universal mounting afforded for the inner end of the tube 38, the mouth piece 39 may be moved into and out of the drawer B, and when moved out of the drawer it may be moved toward and away from the operator, so 105 that the mouth piece 39 is capable of universal adjustment both as respects height and forward and rearward movement to suit the position and convenience of the dictator.

In accordance with the present invention the 110 movement of the mouth piece into and out of the drawer operates automatically some of the controlling and indicating mechanisms of the dictation machine, and also certain safety devices, as next to be explained.

115 Mounted on a rod 40, extending lengthwise across the front of the machine and rotatably carried by suitable brackets 41 extending upwardly from the base plate 10, is a lever 42 having a bifurcated outer end 43, said latter end 120 providing a slot which is adapted to receive the tube 38 and said lever and slot being so disposed that when the tube 38 is moved downwardly into horizontal position from the position shown in Fig. 2, said tube will engage the lower of the 125 bifurcations 43 and rotate the lever 42 about its axis 40 into a substantially horizontal position in which the tube is embraced by the bifurcations 43, and conversely when the tube is moved vertically the lever 42 will be moved around its axis 130 40 from a substantially horizontal position to the position shown in Fig. 2, in which position the tube 38 becomes free of said lever and may thereafter be moved independently thereof.

135 Mounted on brackets 45 extending upwardly from the base plate 10 is a rotatable rod 46 disposed rearwardly of and above the rod 40, as shown in Fig. 2. Said rod may be square or round in cross section, and suitably attached thereto adjacent the brackets 45 are the hubs 140 47 of a pair of arms 48 which carry the scale 49. Slidably mounted on said rod 46 is a spool 50 on which is mounted for rotation relative thereto, but for axial movement therewith, a collar 50', the latter being connected to the carriage 145 21 by a rod 51 so that said spool is caused to move lengthwise of the rod 46 by movement of the carriage as the recording and reproducing mechanism carried thereby traverses the tablet 14. Said spool carries an arm 52 that termi- 150

nates in an index device or pointer 53 cooperatively disposed to move along the scale 49 so that the position of the recording and reproducing mechanism with respect to the tablet 5 is always correctly indicated by the position of the pointer 53 with respect to the scale 49. Although the pointer may be so related with respect to the scale as to move therewith around the axis of the rod 46 whenever the scale is 10 moved into operative position as hereinafter explained, the spool 50 is preferably moved positively with said rod, said rod, if square, engaging a square opening in the spool 50, or if round, being keyed to said spool, so that while the 15 spool may be moved lengthwise of the rod by the rigidity of the connection between collar 50' and rod 51 to cause the pointer 53 to correctly indicate on the scale 49 the position of the recording and reproducing mechanism with respect to the tablet, said spool and pointer must 20 partake of the rotary movement of the rod 46 simultaneously with the scale 49.

Suitably attached to the rod 46 is an arm 54 to which is pivoted at 55 one end of a link 56 25 which, at its opposite end, is pivoted at 57 to the end 58 of the lever 42. When the tube 38 is disposed within the drawer and the lever 42 is disposed horizontally as heretofore described, the rod 46 has been turned through the link 56 30 so that the scale 49 and pointer 53 are depending within the drawer, but when the tube 38 is moved upwardly to the position shown in Fig. 2, lever 42 is rotated in a clockwise direction around its axis 40, and through link 56 the rod 46 is 35 rotated so as to move the arms 48 and 52 upwardly and locate the scale 49 and pointer 53 over the top surface 59 of the desk as shown in Fig. 2, for a purpose to be explained hereinafter.

With the parts disposed as illustrated in Fig. 40 2, any movement of the drawer toward closed position would result in a breakage of the scale and pointer mechanism, and if carried far enough, in an injury to the tube 38, and therefore a drawer stop is automatically brought into operation 45 when the tube 38 is moved outwardly and the scale and pointer mechanism are moved into the relative position shown in Fig. 2. Suitably attached to the top of the desk adjacent either side of the drawer B is a pair of stop 50 lugs 60, which may take the form of blocks of any suitable material attached to the top of the desk as by screws 61. Rotatably mounted in brackets 62 on the base plate 10 is a rod 63 which, at each end thereof, has attached thereto 55 a radially and laterally extending stop arm 64 adapted to be moved into the path of a stop lug 60, or rotated out of horizontal alignment therewith, by rotation of the rod 63. Rod 63 carries an arm 64' which is pivotally attached at 65 to a link 66 that, at its opposite end, is pivoted at 67 to an arm 68 extending from the rod 40. Therefore, when the rod 40 is rotated by the bifurcated lever 42 when the mouth piece is moved out of the drawer, the arm 68 on said rod 60 operates the link 66 and arm 64' to rotate the rod 63 and swing the stop arms 64 into horizontal alignment with the stop lugs 60, so that the drawer cannot be closed inwardly to such a 65 position as to injure the scale and pointer mechanism or tube 38. Conversely, when the tube 38 is moved into the drawer, the tube 40 is rotated in the opposite direction to rotate the rod 63 in the opposite direction and thereby move the stop arms 64 out of horizontal alignment with the stop lugs 60.

Movement of the lever 42 may also be utilized for moving into cooperative relationship some of the controlling elements of the dictation machine. For example, in the form shown, the motor 12 is provided with a switch diagrammatically indicated at 70 and the rod 63 has attached thereto an arm 71 that is suitably connected to the operating element of the switch, so that the electric motor may be started and stopped by moving the mouthpiece out of and into the drawer in the manner heretofore described. This manner of control may also be extended to other parts of the machine if desired. For starting and stopping the machine during dictation, any usual or suitable connection may be made to a press button or control lever 75 carried on the tube 38 for hand operation, or connection may be made to a foot control device 76 as shown in Fig. 1 so that the control of the machine may be rendered entirely independent of the hands, or both controls may be provided if desired, these controls acting directly on the motor or on the clutch 18 in the usual or any suitable way.

In view of the capacity of the mouth piece 39 to be moved about the horizontal axis of the tube 31, means are provided to assure that the elbow 33 is rotated into its lowermost position when the mouth piece 39 and tube 38 are moved into the drawer. To this end, a cam plate 80 is carried by the elbow 34 and is designed to 100 cooperate with the lug 81 carried by the front of the drawer. If desired, cam plate 80 may be rotatably mounted on pivot pin 36 and lug 81 may take the form of a roller, as shown. Cam plate 80 is so shaped that as long as the mouth piece is out of the drawer the cam plate 80 is out of engagement with the lug 81, and there is no restriction to the universal movement of the mouth piece. But before the mouth piece 39 105 can be disposed entirely within the drawer the cam plate 80 engages the lug 81, and if the elbow 33 is not in its lowermost position the elbows 33 and 34 are depressed by the engagement of the plate 80 with the lug 81 as the mouthpiece is moved into the drawer, so that the elbows 33 and 110 34 are automatically disposed in their lowermost position. Conversely, until cam plate 80 is moved out of engagement with cam pin 81, mouthpiece 39 can be moved only out of the 115 drawer, i. e. about the axis of the pivot pin 36. 120 125

It is desirable that the recording and reproducing mechanism and the associated feed mechanism be disposed in their neutral position when the drawer is closed, but this is not essential in all cases. If preferred, the top of the desk 130 may be provided with a lug 82 in the path of the button 25 so that if said button is in its inner or recording position it will be moved to its intermediate or neutral position by the closure of the drawer, and if the button is in its outer or 135 reproducing position means may be provided such as a cam projection 83 on the tube 38 for moving said button into its intermediate or neutral position when the mouth piece 39 is moved into the drawer as heretofore described. 140 If mechanism is not so provided for automatically disposing the button 25 in its intermediate or neutral position, it is preferable that the parts be so arranged that the button 25 in its forward or reproducing position will not interfere with 145 the movement of the mouth piece 39 into its lowermost position in the drawer unless care is taken that the drawer stops cannot be rendered inoperative until the button 25 is out of the path of the mouth piece. 150

When the mouth piece 39 is within the drawer all parts of the machine are compactly arranged in a relatively shallow compact unit which by reason of the horizontal relationship of the parts 5 is such that the entire machine may be readily disposed within a conventional drawer of a desk or in an analogous compartment. When it is desired to use the machine, it is only necessary to open the drawer a few inches sufficiently to 10 enable the mouth piece 39 to be moved outwardly, which will also give access to the button 25. Outward movement of the mouth piece causes the tube 38 to move about the horizontal axis defined by the pivot pin 36, swinging the 15 bifurcated lever 42 in a clockwise direction around its axis 40. Rotation of said rod 40 swings the scale and pointer mechanism 49, 52 outwardly into operative relation with the top 20 of the desk, as shown in Fig. 2, and simultaneously the rod 63 is rotated to dispose the drawer stops so that the drawer cannot be closed to a 25 position to injure any of the parts. Also the automatic switch 71 is actuated to start the motor in operation.

25 The mouth piece 39 can be moved into such a position that it is most convenient to the mouth of the operator, and the machine may be controlled by either the manual device 75 or the foot device 76. If the latter control is used, 30 both hands are entirely free for handling such papers as the dictator may desire. As the mouth piece and scale and pointer mechanisms are the only parts of the dictation machine projecting above the top of the desk, any papers being 35 used by the dictator may be placed directly in front of him on top of the desk in the same manner as if no dictation machine were in use. Moreover, the disposition of the scale and pointer permits a letter to which a reply is being dictated 40 to be placed with its lower edge against the usual bottom stop on the edge of the scale and its lateral edge against the usual lateral stop on the scale, so that by cooperation with the scale and pointer the bottom edge of the 45 letter may be used as a notation or correction sheet for indicating the beginning and end of the dictation which relates to that particular letter and also indicating and corrections or other notations concerning the dictation pertaining 50 to the letter. Hence by a suitable notation on the letter the identification of a dictated reply thereto and all notations pertaining thereto can be readily made. As the pointer is not moved with respect to the scale by movement 55 of the scale and pointer into and out of the drawer, the pointer will always properly designate the end of any preceding dictation whenever the dictation machine is brought into use.

When the dictation has been finished the 60 mouth piece 39 may be merely turned down into the drawer. This automatically moves the scale and pointer into the drawer, withdraws the drawer stops from their operative position, and opens the switch of the motor, so that the machine is placed entirely out of operation, and out 65 of the way by closure of the drawer.

It will therefore be perceived that a dictation 70 machine has been provided which is of such construction that it can be readily disposed within a drawer, and whereby movement of the mouth piece into operative position automatically disposes the scale and pointer mechanism with respect to the top of the desk, brings into operation the necessary safety features and puts the machine in condition for operation. At the

same time the mouth piece is so mounted that it can be disposed at any suitable position for the convenience of the operator and retained in such position while leaving the operator's hands free for handling papers or the like. 80 Moreover, the top of the desk is substantially free so that the dictator while retaining his usual position at the desk may have the entire desk top available for papers and yet the dictation machine is directly in front of him. Also the papers in use in dictating may be used as the notation, correction and identification sheets for the dictation. All of the usual controls of the dictation machine are also conveniently disposed so that they are accessible and subject to 85 the usual operation without the dictator moving his position.

While the embodiment of the invention illustrated on the drawings has been described with considerable particularity, it is to be expressly understood that the invention is not restricted thereto as the same is capable of receiving a variety of mechanical expressions. For example, the tube 38 may, if desired, be formed as a plurality of telescopically related sections so 100 that said tube may be extended or contracted to suit the convenience of the operator, or, if it is desired to reduce the distance of travel of the sound waves to a minimum, said tube may be made of a well known form of flexible 105 tubing and suitable means provided to support the mouthpiece and to cooperate with bifurcated lever 42 in the same manner as tube 38. Also, it is within the contemplation of the present invention that the recording and reproducing of the spoken words may be done electrically instead of by sound waves alone as in the embodiment illustrated. Various other changes which will now readily suggest themselves to those skilled in the art, may be made in the 115 details of construction, arrangement and proportion of parts, and some features used without other features, without departing from the spirit of this invention. Reference is therefore to be had to the appended claims for a definition of the invention.

What is claimed is:

1. In a dictation machine arranged to be disposed within a drawer and in combination with mechanism for recording sound on a tablet, a 125 mouth piece connected with said recording mechanism and adapted to receive the sound to be recorded on said tablet, means housed within the drawer for mounting said mouth-piece for vertical movement into and out of said 130 drawer and for movement about an axis at right angles to the axis of said vertical movement, and means positively actuated by the vertical movement of said mouth piece for rendering said machine operative and inoperative. 135

2. In a dictation machine arranged to be disposed within a drawer and in combination with mechanism for recording sound on a tablet, a sound receiving mouth piece for said recording mechanism movable into and out of the drawer, 140 scale and pointer mechanism operatively connected with said recording mechanism for indicating the position thereof with respect to said tablet, said scale and pointer mechanism also being mounted for movement into and out of the drawer, and means operated by movement of the mouth piece into and out of the drawer for moving the scale and pointer mechanism into and out of the drawer. 145

3. In a dictation machine arranged to be dis-

posed within a drawer and in combination with mechanism for recording sound on a tablet, a sound receiving mouth piece for said recording mechanism mounted for vertical movement into 5 and out of the drawer and for movement about an axis at right angles to the axis of said vertical movement, a switch for controlling said mechanism and means positively operated by the vertical movement of said mouth piece into 10 and out of the drawer for opening and closing said switch.

4. In a dictation machine arranged to be disposed within a drawer and in combination with mechanism for recording sound on a tablet, a sound receiving mouth piece for said recording mechanism movable into and out of the drawer, and means operated by the movement of said mouth piece out of the drawer for preventing closure of the drawer while the mouth piece is 20 projecting exteriorly thereof.

5. In a dictation machine arranged to be disposed within a drawer and in combination with mechanism for recording sound on a tablet, a sound receiving mouth piece for said recording mechanism movable into and out of the drawer, scale and pointer mechanism operatively connected with said recording mechanism for indicating the position thereof with respect to said tablet, said scale and pointer mechanism also 25 being mounted for movement into and out of the drawer, means operated by the movement of the mouth piece for moving said scale and pointer mechanism into and out of the drawer, and stop mechanism operatively disposed by the movement 30 of the mouth piece out of the drawer for preventing closure of the drawer while the scale and pointer mechanism are projecting exteriorly thereof.

6. In a dictation machine arranged to be disposed within a drawer and in combination with mechanism for recording sound on a tablet, a sound receiving mouth piece for said recording mechanism movable into and out of the drawer, means supporting said mouth piece and movable 45 about angularly related axes so that said mouth piece may be universally adjusted to suit the position of the dictator, and members on said supporting means and the drawer in engagement when said mouth piece is disposed in said drawer 50 for preventing movement of said mouth piece about one of said axes.

7. In a dictation machine arranged to be disposed within a drawer and in combination with mechanism for recording sound on a tablet, a sound receiving mouth piece for said recording mechanism movable into and out of the drawer, means supporting said mouth piece and movable about angularly related axes so that said mouth piece may be universally adjusted, and means 60 operated by the movement of the mouth piece into the drawer and cooperating with said supporting means for moving said supporting means into such position that all parts thereof are disposed within the drawer.

65 8. In a dictation machine arranged to be disposed within a drawer and in combination with mechanism for recording sound on a tablet, scale and pointer mechanism operatively connected with said recording mechanism for indicating the position thereof with respect to said tablet, said scale and pointer mechanism being mounted for movement into and out of the drawer, and means for preventing closure of the drawer while said scale and pointer mechanism 70 are projecting therefrom.

9. In a dictation machine arranged to be disposed within a drawer and in combination with mechanism for recording sound on a tablet, a sound receiving mouth piece for said recording mechanism movable into and out of the drawer, a sound conveying tube between said mouth piece and recording mechanism and means separate from said sound conveying tube for preventing closure of the drawer while said mouth piece is projecting therefrom. 80

10. In a dictation machine arranged to be disposed within a desk drawer and in combination with mechanism for recording sound on a tablet, a sound receiving mouth piece for said recording mechanism movable into and out of the drawer, scale and pointer mechanism operatively connected with said recording mechanism for indicating the position thereof with respect to said tablet, and means operated by movement of said mouth piece out of the drawer 90 for disposing said scale and pointer mechanism adjacent the top of the desk. 95

11. In a dictation machine arranged to be disposed within a drawer and in combination with mechanism for recording sound on a tablet, a sound receiving mouth piece for said recording mechanism movable into and out of the drawer, auxiliary devices operatively connected with said recording mechanism for indicating to the dictator the operative position of said mechanism, 100 said auxiliary devices being disposed in inoperative position when said mouth piece is positioned within the drawer; and means automatically operated by the movement of said mouth piece for moving said auxiliary devices into 105 operative relationship.

12. In a dictation machine arranged to be disposed within a drawer and in combination with mechanism for recording sound on a tablet, a mouth piece connected with said recording 115 mechanism and adapted to receive the sounds to be recorded on said tablet, means housed within the drawer for mounting said mouth piece for vertical movement into and out of said drawer, means for controlling the sound 120 recording operation of said mechanism, and means positively operated by the movement of the mouth piece into and out of the drawer for automatically operating said controlling means. 125

13. In a dictation machine arranged to be disposed within a drawer and in combination with mechanism for recording sound on a tablet, a sound receiving mouth piece for said recording mechanism movable into and out of the drawer, a lever operated by the movement of said mouth 130 piece, and means operated by said lever for preventing closure of the drawer while said mouth piece projects exteriorly thereof.

14. In a dictation machine arranged to be disposed within a drawer and in combination with mechanism for recording sound on a tablet, a mouth piece connected with said recording 135 mechanism and adapted to receive the sounds to be recorded on said tablet, means housed within the drawer for mounting said mouth-piece for vertical movement into and out of said drawer, a lever positively operated by the movement of said mouthpiece into and out of said drawer, and means operated by said lever for automatically controlling the operative condition 140 of said sound recording mechanism. 145

15. In a dictation machine arranged to be disposed within a drawer and in combination with mechanism for recording sound on a tablet, a sound receiving mouth piece for said record- 150

- ing mechanism movable into and out of the drawer, a lever operated by the movement of said mouth piece, scale and pointer mechanism operatively connected with said recording mechanism for indicating the position thereof with respect to said tablet, said scale and pointer mechanism also mounted for movement into and out of the drawer, and connections between said lever and scale and pointer mechanism 5 whereby said mechanism moves into and out of the drawer with the mouth piece.
16. In a dictation machine arranged to be disposed within a drawer and in combination with mechanism for recording sound on a tablet, a sound receiving mouth piece for said recording mechanism movable into and out of the drawer, a lever operated by a portion of the movement of the mouth piece with respect to the drawer, means supporting the mouth piece 10 and permitting universal movement thereof independently of said lever after said mouth piece has been moved out of the drawer, scale and pointer mechanism operatively connected with said recording mechanism for indicating the position 15 thereof with respect to said tablet, and means for moving said scale and pointer mechanism into and out of the drawer when said lever is operated by the movement of said mouth piece.
17. In a dictation machine arranged to be disposed within a drawer and in combination with mechanism for recording sound on a tablet, a sound receiving mouth piece for said recording mechanism movable into and out of the drawer, 20 a lever operated by a portion of the movement of the mouth piece with respect to the drawer, means supporting the mouth piece and mounted to permit universal movement of said mouthpiece independently of said lever after said mouth piece has been moved out of the drawer, said means normally occupying a substantially horizontal position within said drawer when said mouthpiece is disposed therewithin, but movable out of said position when the mouthpiece 25 is moved out of the drawer, scale and pointer mechanism operatively connected with said recording mechanism for indicating the position thereof with respect to said tablet, means for moving said scale and pointer mechanism into 30 and out of the drawer when said lever is operated by the movement of said mouth piece, and means operated by the movement of the mouth piece into the drawer for restoring said supporting means to said normal position.
18. In a dictation machine adapted to be disposed in a drawer, the combination of means for supporting and rotating a tablet, recording mechanism and feed mechanism therefor, a motor adapted to drive said tablet rotating means and said feed mechanism, all of said elements being disposed in substantially horizontal alignment and constituting a relatively shallow unit adapted to be disposed within a drawer, a mouth piece operatively connected to said recording mechanism, and means housed within and adjacent the front edge of said drawer and also in substantially horizontal alignment with said tablet rotating means for supporting said mouthpiece for vertical movement into and out 45 of the drawer and for movement about a second horizontal axis at right angles to the axis of said vertical movement and parallel to the front of the drawer.
19. In a dictation machine adapted to be disposed in a drawer, the combination of means 50 for supporting and rotating a tablet, recording mechanism and feed mechanism therefor, a motor adapted to drive said tablet rotating means and said feed mechanism, all of said elements being disposed in substantially horizontal alignment and constituting a relatively shallow unit adapted to be disposed within a drawer, a mouth piece operatively connected to said recording mechanism, and means housed within and adjacent the front edge of said drawer and also in substantially horizontal alignment with said tablet rotating means for supporting said mouthpiece for vertical movement into and out of the drawer and for movement about a second horizontal axis at right angles to the axis of said vertical movement and parallel to the front of the drawer.
20. In a dictation machine adapted to be disposed in a desk drawer, the combination of means for supporting and rotating a tablet, recording mechanism and feed mechanism therefor, a motor adapted to drive said tablet rotating means and said feed mechanism, all of said elements being disposed in substantially horizontal alignment and constituting a relatively shallow unit adapted to be disposed within a drawer of the desk, and scale and pointer mechanism operatively connected with said recording mechanism for indicating the position thereof with respect to said tablet, said scale and pointer mechanism being movable into and out of the drawer relatively to said recording mechanism and adapted to assume a cooperative relation with a sheet of paper lying on the top of the desk.
21. In a dictation machine, in combination with means for supporting and rotating a tablet, recording mechanism and feed mechanism therefor, a motor adapted to drive said tablet rotating means and said feed mechanism, all of said elements constituting a relatively shallow unit, a movable desk drawer enclosing said machine, and scale and pointer mechanism operatively connected with said recording mechanism for indicating the position thereof with respect to said tablet, said scale and pointer mechanism being movable relatively to said recording mechanism about an axis substantially parallel to the face of said drawer and into cooperative relation with the top of the desk when the drawer is open by a relatively small amount.
22. In a dictation machine, in combination with means for supporting and rotating a tablet, recording mechanism and feed mechanism therefor, a motor adapted to drive said tablet rotating means and said feed mechanism, all of said elements constituting a relatively shallow unit, a movable desk drawer enclosing said machine, a sound receiving mouth piece for said recording mechanism, and a sound transmitting tube supporting said mouth piece and having joints providing movement about right angularly related horizontal axes, said joints being disposed adjacent the front edge of the drawer whereby said tube and mouth piece are movable into and out of said drawer when said drawer is open only to an extent substantially equal to the width of said tube and mouthpiece.
23. In a dictation machine, in combination with means for supporting and rotating a tablet, recording mechanism and feed mechanism therefor, a motor adapted to drive said tablet rotating means and said feed mechanism, all of said elements constituting a relatively shallow unit, a movable desk drawer enclosing said

machine, a sound receiving mouth piece connected to said recording means and means housed within and adjacent the front edge of said drawer for supporting said mouthpiece for 5 movement into and out of said drawer about an axis at right angles to the front of said drawer when said drawer is open only to an extent substantially equal to the width of said tube and mouthpiece whereby said machine and 10 mouthpiece may be positioned for use by a dictator occupying a normal position at the desk and without restriction of the top surface of the desk.

24. In a dictation machine, in combination 15 with means for supporting and rotating a tablet, recording mechanism and feed mechanism therefor, a motor adapted to drive said tablet rotating means and said feed mechanism, all of said elements constituting a relatively shallow unit, 20 a movable desk drawer enclosing said machine, devices for controlling the sound recording operation of said machine disposed to be accessible when the drawer is open by a relatively small amount, a sound receiving mouth piece connected 25 to said recording mechanism, means housed within and adjacent the front edge of said drawer for supporting said mouthpiece for movement into and out of the drawer when the drawer is open by a relatively small amount, 30 and means operated by the movement of said mouthpiece into and out of said drawer for automatically changing the position of certain of said controlling devices.

25. In a dictation machine, in combination 35 with means for supporting and rotating a tablet, recording mechanism and feed mechanism therefor, a motor adapted to drive said tablet rotating means and said feed mechanism, all of said elements constituting a relatively shallow unit, 40 a movable desk drawer enclosing said machine, scale and pointer mechanism operatively connected with said recording mechanism for indicating the position thereof with respect to said tablet, said scale and pointer mechanism 45 being movable into cooperative relation with the top of the desk when the drawer is open by a relatively small amount, a sound receiving mouth piece for said recording mechanism movable into and out of the drawer when the 50 drawer is open by a relatively small amount, and connections between said scale and pointer mechanism and said mouth piece whereby they move into and out of the drawer together.

26. In a dictation machine, in combination 55 with means for supporting and rotating a tablet, recording mechanism and feed mechanism therefor, a motor adapted to drive said tablet rotating means and said feed mechanism, all of said elements constituting a relatively shallow 60 unit, a movable desk drawer enclosing said machine, a sound receiving mouth piece connected to said recording mechanism, a sound transmitting tube supporting said mouthpiece and connected to said recording mechanism at a 65 point within and adjacent the front edge of the drawer, said connection permitting movement of said tube and mouthpiece into and out of the drawer when the drawer is open only to an extent substantially equal to the width of said tube and mouthpiece and control mechanism for said machine positively operated by the movements of said mouth piece into and out of said drawer.

27. In a dictation machine, in combination 75

with means for supporting and rotating a tablet, recording mechanism and feed mechanism therefor, a motor adapted to drive said tablet rotating means and said feed mechanism, all of said elements constituting a relatively shallow unit, a movable desk drawer enclosing said machine, a scale and pointer mechanism operatively connected with said recording mechanism for indicating the position thereof with respect to said tablet, said scale and pointer mechanism being movable relatively to said recording mechanism into and out of said drawer, and means for preventing closure of said drawer while said mechanism is projecting exteriorly therefrom.

28. In a dictation machine, in combination 80 with means for supporting and rotating a tablet, recording mechanism and feed mechanism therefor, a motor adapted to drive said tablet rotating means and said feed mechanism, all of said elements constituting a relatively shallow unit, a movable desk drawer enclosing said machine, a sound receiving mouth piece movable into and out of said drawer, a jointed conduit connecting said mouth piece and recording mechanism, means operated by the movement of said mouth piece into said drawer and cooperating with said conduit for disposing said conduit within said drawer, and means for preventing pinching of said conduit by closure of said drawer while said mouth piece is projecting exteriorly therefrom.

29. In a dictation machine, in combination 85 with means for supporting and rotating a tablet, recording mechanism and feed mechanism therefor, a motor adapted to drive said tablet rotating means and said feed mechanism, all of said elements constituting a relatively shallow unit, 90 a movable desk drawer enclosing said machine, a sound receiving mouth piece connected to said recording mechanism and movable into and out of said drawer, stop means adapted to be moved into cooperative relation to prevent closure of the drawer when said mouthpiece is projecting exteriorly therefrom, and mean actuated by the movement of said mouth piece for starting and stopping said motor and for simultaneously moving said stop means into and out of cooperative relation.

30. In a dictation machine arranged to be 95 disposed within a drawer and in combination with mechanism for recording sound on a tablet and for reproducing said sound after being recorded, a member movable to three positions and adapted to place said mechanism in recording, neutral and reproducing condition, respectively, and means for automatically moving said member to neutral position from one of said other positions upon closure of the drawer.

31. In a dictation machine arranged to be 100 disposed within a drawer and in combination with mechanism for recording sound on a tablet and for reproducing said sound after being recorded, a mouthpiece for said recording and reproducing mechanism movable into and out of the drawer, a member movable to three positions and adapted to place said mechanism in recording, neutral and reproducing condition, respectively, and means for automatically moving said member to neutral position from one of said other positions upon movement of the mouthpiece into the drawer.

32. In a dictation machine arranged to be 105 disposed within a drawer and in combination 110

with mechanism for recording sound on a tablet and for reproducing said sound after being recorded, a member movable to two positions and adapted to place said mechanism in recording and neutral condition, respectively, and means for automatically moving said member from recording to neutral position upon movement of the drawer to closed position.

33. In a dictation machine arranged to be disposed within a drawer and in combination with mechanism for recording sound upon a

tablet and for reproducing said sound after being recorded, a mouthpiece for said recording and reproducing mechanism movable into and out of the drawer, a member movable to two positions and adapted to place said mechanism in reproducing and neutral condition, respectively, and means for automatically moving said member from reproducing to neutral position upon movement of the mouthpiece into the drawer.
